UNITED STATES PATENT OFFICE.

ELMER A. SPERRY, OF BROOKLYN, NEW YORK, ASSIGNOR TO SPERRY DEVELOPMENT COMPANY, OF DOVER, DELAWARE, A CORPORATION OF DELAWARE.

PISTON FOR INTERNAL-COMBUSTION ENGINES.

Application filed January 14, 1922. Serial No. 529,314.

This invention relates to pistons for internal combustion engines and has to do with the cooling thereof.

The object of the invention is to devise a method and means whereby a cooling fluid may be positively circulated within the piston to transfer the heat from the end of the piston with which the hot gases come in contact to the cooler portions thereof, and to cause the sides of a piston thus cooled to move intermittently into closer contact with the adjacent wall of the cylinder with which it operates.

Referring to the drawings wherein I have shown what I now consider to be the preferred form of my invention:

Fig. 1 is a vertical cross section of a piston constructed in accordance with my invention; a fragment of the cylinder also being shown.

Fig. 2 is a section taken at right angles to Fig. 1.

Fig. 3 is an enlarged sectional detail of the lower portion of the piston.

Fig. 4 is a section taken on line 4—4 of Fig. 2, omitting the piston rod.

Fig. 5 is a vertical sectional view of a piston showing a modified form of the invention.

Fig. 5^A is a detail of an expansion chamber.

Fig. 6 is a section taken on line 6—6 of Fig. 5.

Fig. 7 is a vertical section of a piston illustrating a further modification.

Fig. 8 is a diagrammatic view of a piston in operation.

Fig. 9 is a modified form of the invention.

Fig. 10 is a sectional detail taken on line 10—10 of Fig. 9.

In Figs. 1 to 4 inclusive, the piston 1 is shown as being hollow and may be provided with internal bosses 2 for the wrist pin 3 which may be secured therein by set screws.

The hub 5 of the connecting rod 6 is mounted on said wrist pin in the usual manner.

Within the piston I have shown a wall 7 cooperating with the main wall 8 of the piston to form a chamber 9 adapted to contain a cooling fluid. The wall 7 may be cast as an integral part of the piston, and may have an opening 10 in the upper end thereof, which may be closed by a plug 11, secured to the wall by bolts 12. The chamber 9, as

shown at 13 may pass over the top of the hubs 2 which form the supports for the pin 3, and down the sides of the piston normal to the wrist pin. Thus, on the sides 14, 15 of the piston normal to the wrist pin, channels 16, 17 may extend to the lower end of the piston as shown in Fig. 1, while on the sides 18, 19 under the ends of the pin, the cooling fluid chamber may be omitted as is seen in Fig. 2, and, as shown in Fig. 4, separate channels extend down two sides of the piston.

These channels may be joined at the bottom to permit the flow of liquid between them to maintain equalization of liquid on both sides. To this end, I may employ a pair of end members 20, 21 attached to the lower end of the piston, one thereof being associated with each of the depending channels. Any suitable method may be employed to secure said members in position. I have here shown said members as having threaded projections 22 screwed into the piston. Screws 23 may also be employed. Packing 25 may be employed between said members and the piston. Any suitable conduit, such as pipe 24 may run between members 20, 21 and be connected by passages 26, 27 with channels 16, 17. The passage 26 is shown as leading into a tube 28 having an opening 29 in the lower part of channel 16. The said tube 28 may extend to the upper part of chamber 9 as illustrated in Fig. 1.

In channel 17 I have shown a tube 30 connected with a passage 31 normally closed by a plug 32. The cooling fluid may be poured into the chamber 9 through this tube, or it may be forced in while the piston is in the upright position in the cylinder. In the latter case, liquid may be injected into the chamber up to the height of the top of tube 30 without running out again when plug 32 is being inserted. Should it be desirable at any time to drain the liquid from the piston, this may be done by removing plug 33 in the passage 26.

The inner side of the piston head 34 may be provided with ribs 35. These ribs may also be integral with the sides of the piston and may serve the double function of cooling fins and braces for the head.

Presuming the piston to be partially filled with liquid, as for instance to the top of tube 30, reciprocatory downward and upward movement of the piston will cause the liquid

to be thrown up and down. The liquid will thus be circulated to all parts of chamber 9 and channels 16, 17. The liquid will, in this way, extract heat from the upper end of the 5 piston which is the hotter end and distribute this heat to the lower or cooler portions.

Any tendency of the liquid to collect in a larger quantity in one of the channels 16, 17 than in the other will, of course, be overcome by the flow between the channels 10 through conduit 24.

It will be understood that ordinarily, to move up and down in the closed piston, the liquid would have to compress the air cushion 15 in the top of the piston cavity and at the same time create a vacuum in the bottom of the cavity. Obviously, this would cause great resistance to proper circulation. In fact, the top of the liquid column or columns 20 would break up and splash about while the lower part would tend to remain fixed. With the tube 28 extending to the top of the piston and having a hole 29 at the bottom, however, a ready transfer of air from the 25 top of the bottom of the piston may take place. Thus a sudden downward thrust of the piston will readily result in a relatively upward thrust of the liquid, the air cushion being transferred from the top of the piston 30 cavity to the bottom.

It will, of course, be seen that where the transfer tube 28 is filled with liquid to the level of the liquid in the cavity 9, there will be an upward thrust within the tube theoretically equal to the downward air pressure. The friction between the tube and the liquid 35 therein, however, is relatively much greater than in the case of the liquid in cavity 9, so that in reality the downward air pressure in the tube is greater than the upward liquid 40 pressure therein. Also the tendency of the larger column to create a vacuum will aid in drawing the liquid out of the tube through the bottom.

45 I may, if desired, place a valve at the bottom of the tube to prevent the inflow of liquid during the upward stroke of the piston, but permitting the outflow of air during the downward stroke. Such a valve may comprise a collar 29' on the tube 28 and adapted 50 during the downward stroke to be thrust upwardly against a stop pin 29'', thus uncovering the opening 29 and to be thrust downwardly during the upward stroke of the piston to cover said opening. Thus 55 when operating, there will be practically no liquid in the tube, and therefore, no counter-pressure to be overcome by the air in the tube, and a vacuum in the bottom will actually serve to draw air from the opening in 60 the bottom of the tube.

I have also found that by withdrawing the air or at least a part of it from the piston, the liquid may be very readily tossed about 65 when the air transfer tube 28 is omitted. To

withdraw the air, plug 32 may be removed and the vacuum pump connected in its place. In this event, any suitable valve 36 may be employed to close the passage 31 to prevent leakage when the pump is detached.

Referring to the kind of liquid that may be employed in the piston for transferring the heat, I have found oil to give satisfactory results, although obviously any other suitable liquid may be used.

Figs. 5 and 6 illustrate a modified form of my invention. In this form, the cavity 9' is shown as including the downwardly extending channels 16', 17' on the opposite sides of the piston 1'; the said channels being joined at the bottom by a passage 24' indicated by dotted lines. Cylindrical member 37 is shown as placed in the cavity, and may be secured in position by the engagement of flanges 38 thereon with cooperating flanges 39 on the inside wall 7' and a plate or plug 40 screwed into the portion 41 of the inside wall. A ring member 42 secured to wall 7' by screws 43 and reaching under said plug may serve to prevent the latter from working loose when the piston is in use. An expansion chamber 24^A may be connected to the cavity through channel 24'.

A centrally located shaft 44 secured at 45 to the piston head 34' and lodged in a boss 46 on plug 40 may serve as the guide rod of a plunger 47 adapted to reciprocate up and down in the cylinder 37. A large opening 48 is provided in the top of the cylinder 37 and numerous smaller openings 49 around 100 the sides near the bottom thereof.

A sloping partition 50 may be placed between the wall 8' of the piston and the wall of the cylinder 37. As shown, this partition is formed integrally with the wall 8' 105 and adapted to fit around the cylinder 37 when the latter is placed in position. The said partition is shown as extending around the greater part of the piston, but is omitted on the side of the channel 16' by being cut off at 51. Thus, direct communication is cut off between the upper part of the cavity 9' and the channel 17', but not between said upper part and channel 16'.

Presuming the cavity 9' to be completely 115 filled with oil or other liquid, movement of the plunger 47 upwardly will cause a movement of the liquid throughout the whole piston in the direction of the arrows. The liquid is thus forced out through the top of the cylindrical member 37 and downwardly on all sides thereof, guided by partition 50 to channel 16'; through said channel and passage 24' to channel 17'; upward through the latter channel and over the top of the extended portion 52 of the inside wall 7', which portion is provided to induce complete circulation in the upper part of the channel, and then downwardly and through openings 49 into the lower end of 125

cylinder 37 to follow the upward movement of the plunger 47. Downward movement of the plunger will, of course, cause a reverse movement of the liquid throughout the piston. Thus, as the piston reciprocates up and down during operation of the engine, the inertia of the plunger will cause it to reciprocate in its cylinder to induce the aforesaid back and forth movement of the liquid. As the liquid sweeps back and forth and circulates generally through the piston, it will extract heat from the hotter portions of the piston and distribute the same to the cooler portions.

15 The heat which the lower portion of the piston absorbs from the circulating liquid, will in turn be absorbed by the medium surrounding said lower portion. Thus, the wall 53 will be cooled by the air or other medium in the open cavity 54 of the piston, while the wall 55 will transfer heat from the jacket passages 16' and 17' etc. to the adjacent wall 56 of the engine cylinder, whence it will be extracted by the circulating cooling fluid in the jacket 57 in the usual manner. The transfer of heat from wall 55 to wall 56, however, tends to take place rather slowly owing to the high heat insulating qualities of the oil film existing between the 20 two walls. In order to increase the rate of heat transfer, therefore, it is necessary to decrease the thickness of the oil film and thereby decrease its heat resistance. To accomplish this I propose to administer side 25 pressure to the piston to squeeze out the greater part of the oil film and force the piston into closer relation with the cylinder wall. This is found to cause a chilling of the wall of the piston on the side which is brought closer to the cylinder. As soon as the pressure is removed, however, and the piston assumes its normal centralized position in the cylinder, heat equalization takes place very rapidly; the chilled portion of 30 the piston wall absorbing heat from the hotter adjacent portions and from the liquid within. Such pressure is found to enhance greatly the rate of heat transfer in these regions, and by applying the pressure alternately on opposite sides, the effect may be doubled.

While several suitable methods may be devised for applying the side pressure to the piston, I have found it convenient to employ 35 the type of construction wherein the piston rod 58 is connected directly between the piston and the engine crank shaft 59 as indicated in Fig. 8. Presuming the crank shaft to be turning in the direction represented by the arrow 60 in Fig. 8, it will be recognized that the downward pressure of the expanding gas on the piston coupled with the upward reactionary force of the crank shaft will result in a side thrust of the piston as 40 indicated by arrow 61. Also, during the

compression stroke of the piston, the rod being in the dotted line position 58' and pressing upwardly while the gases being compressed exert a downward pressure, a side thrust of the piston in the direction of arrow 62 will take place. These side thrusts are of great force and serve very well to squeeze the oil out from between the piston and cylinder walls on the side of the piston toward which the pressure is exerted.

70 In the form of the invention shown in Fig. 5, the cooling liquid cavity 9' may be completely filled with oil, or other liquid, and while I may employ one or more expansion chambers, such as disclosed in my 75 copending application, Serial No. 486,181 for pistons for internal combustion engines, to absorb the expansion of the liquid when it becomes heated, I prefer to accomplish this result by another method. This method 80 comprises reducing the pressure of the liquid upon the piston when the liquid is in its normal or cold state, to a point below atmospheric pressure, so that when the liquid becomes heated its expanding pressure will 85 not rise sufficiently above atmospheric pressure to crack the piston walls. One method by which this initial contracting power may be imparted to the liquid is by heating the piston and liquid to a predetermined degree 90 before the liquid is sealed within the piston. While the piston and liquid are thus heated the chamber 9' may be sealed. Subsequent cooling will result in the contracting effect 95 of the liquid.

100 Fig. 7 illustrates a further modification of the invention. In this form the cavity or chamber 9'' may have its upper portion separated from the downwardly extending channels 16'', 17'', by a partition 64. This partition, however, is provided with trap valves 65, 66 held normally closed by springs 67, 68. One of said valves, as for instance valve 65, may be adapted to be opened into the upper part of chamber 9'' by pressure 105 against its lower surface, while the valve 66 may be adapted to be opened into channel 17''.

110 The piston is only partially filled in this instance, but whether it be filled to a point above or below the trap valves does not affect its manner of operation. Presuming it to be filled to the point represented by the line 69, and the space above evacuated, downward thrust of the piston will cause a relative upward thrust of the liquid in the channels 16'', 17''. Valve 65 will be forced open, permitting the liquid in channel 16'' to enter and flood the upper part of the chamber. At the end of the downward stroke and the beginning of the upward stroke, valve 65 will be closed and valve 66 opened, while the liquid is forced into channel 17'', flowing through passage 24'' (indicated by dotted lines) into channel 16'' 115 120 125 130

Thus it will be seen that when the piston is in operation the liquid will be caused to circulate therethrough in one direction.

Obviously, the side thrust of the piston 5 may be employed in this, as well as in the other forms of the invention. In this connection it may be stated that the application of the lateral force is preferably at a point substantially midway between the upper and 10 lower extremities of the surface to be cooled, so that equal pressure will be applied throughout the entire distance. To accomplish this, the wrist pin should be located at a point substantially midway between 15 the upper and lower ends of the piston, as shown.

In Fig. 9 I have shown a modified form of the invention. In this form I have shown a cavity 9^a within the upper end of the 20 piston 1^a, and a second cavity 9^b, within the cavity 9^a and separated therefrom by a partition 70. The two cavities are joined in the upper portion of the piston by an opening 71 in the partition, while the lower 25 part of cavity 9^b may communicate with the outer cavity through holes 72 in said partition. The lower part of cavity 9^b may be closed by a plate 73 secured by bolts 74 to a flange 75 on the partition. Within the 30 cavities I have shown a central shaft 75' bearing at 76 in plate 73 and at 77 in the piston head. Fixed on this shaft within the opening 71 I have shown a propeller 78. A pair of fixed shafts 79, 80 are also provided 35 in the cavity 9^b, being secured at 81, 82 to the plate 73, and attached to a yoke 83 at their upper ends.

The bottom of shaft 75' may have fixed thereon at 84 a circumferential spring housing 85. Coiled within said housing and secured thereto at 86 is shown a spring 87. The inner part of this spring may in turn be fixed as at 88 to a ring 89. Without the shaft 75' I have shown a sleeve 90 having 45 bearings at 91, 92 on the housing 85 and yoke 83 respectively. The lower end of said sleeve may have an enlarged portion 93, (see also Fig. 10) positioned within the ring 89 and provided with graduated recesses 94 within which may be placed steel balls 95. When the sleeve is rotated clockwise it will be seen that the balls will be wedged against the ring 89. The ring being thus clutched will rotate with the sleeve to 55 wind up the spring 87. A pawl 96 carried by an arm 97 integral with plate 73 may be provided to engage ratchet teeth 98 on the ring to prevent it from turning backward when not gripped by the clutch.

60 An inertia member 99 is adapted to slide up and down over the sleeve 90 and the guide rods 79, 80. A pin 100 fixed in member 99 reaches into a spiral groove 101 in the sleeve 90.

The operation is as follows: When the

piston 1^a is thrust downwardly, the relative upward thrust of the inertia member 99 will cause the sleeve to rotate, let us say, in a clockwise direction. The balls 95 will clutch ring 89 and wind up the spring 87 as we have seen, and the pawl 96 will prevent the ring from turning backward. When the member 99 moves downwardly, the sleeve 90 will rotate in a counterclockwise direction, the balls 95 releasing the ring 89 so that the latter is not affected. Thus, each upward movement of member 99 will serve to wind up spring 87. The energy thus stored in spring 87 will cause the housing member 85 to turn clockwise, and being fixed on shaft 75', to cause said shaft and propeller 78 to rotate similarly. Presuming the piston to be filled with oil or other liquid, such liquid will be caused to circulate upwardly through the inner cavity 9^b, through opening 71 to the outer cavity 9^a, and downwardly therethrough; flowing into the inner cavity again through openings 72, or, obviously, the liquid may be caused to take the longer circuit as in Fig. 5 before reentering cavity 9^b; in which case the diagonal partition 50 may be used.

In order to cushion the thrust of the inertia member 99 at the ends of its strokes, springs 102 or other suitable means may be employed.

It will, of course, be understood that the mechanism contained in the inner cavity 9^b, including the propeller 78 may be placed in the inner cavity of the piston shown in Fig. 5. In such case, a more positive circulation of the cooling oil through the lower end of the piston will take place as indicated by the arrows in said Fig. 5.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combinations and relations described, some of these may be altered and others omitted without interfering with the more general results outlined, and the invention extends to such use.

Having described my invention what I claim and desire to secure by Letters Patent is,

1. In combination, a piston adapted to reciprocate within a cylinder, a chamber within said piston and filled with fluid, a second cylinder in said chamber and a plunger in said secondary cylinder for causing circulation of the fluid.

2. In combination, a hollow piston adapted to reciprocate within a cylinder, a chamber

- for a cooling fluid adjacent the inner wall of said piston, means associated with said chamber for causing circulation of the fluid when the piston reciprocates for causing the fluid to flow down one side of said piston and up the other side, and a diagonally disposed baffle within said chamber interposed between the upstream and the downstream of said fluid.
5. In combination, a hollow piston adapted to reciprocate within a cylinder, a chamber for a cooling fluid adjacent the inner wall of said piston, means associated with said chamber for causing circulation of the fluid when the piston reciprocates, and means for directing the moving fluid down one side of the piston, across the bottom and up the other side.
10. 3. In combination, a hollow piston adapted to reciprocate within a cylinder, a chamber for a cooling fluid adjacent the inner wall of said piston, means associated with said chamber for causing circulation of the fluid when the piston reciprocates, and means for directing the moving fluid down one side of the piston, across the bottom and up the other side.
15. 4. In combination, a hollow piston adapted to reciprocate within a cylinder, a wrist pin in said piston, a chamber for a cooling fluid adjacent the inner wall of said piston, means for inducing circulation of the fluid, and means for directing the moving fluid down one side of the piston normal to the wrist pin axis, across the bottom and up the other side.
20. 5. In combination, a hollow piston adapted to reciprocate within a cylinder, a wrist pin in said piston, a chamber for a cooling fluid adjacent the inner wall of said piston, means dividing said chamber into inter-communicating compartments, said compartments being normal to the axis of the wrist pin and on opposite sides thereof and a fluid impeller adapted to work within said piston, one side of said impeller being connected with one of said compartments and the other side with another compartment.
25. 6. In combination, a hollow piston adapted to reciprocate within a cylinder, a wrist pin in said piston, a chamber adjacent the inner wall of said piston for a cooling fluid, means dividing said chamber into intercommunicating compartments, said compartments being normal to the axis of the wrist pin and on opposite sides thereof and a plunger adapted to work within said piston, one side of said plunger being connected with one
- of said compartments and the other side with another compartment and deflecting means associated with said piston for directing the flow of the cooling fluid.
7. In combination, a hollow piston, a chamber adjacent the inner wall of said piston, said chamber being divided into intercommunicating compartments containing a cooling fluid, deflecting means adapted when the fluid is in motion due to reciprocation of the piston to direct the fluid from one compartment to another on one side of the piston, and means for directing said fluid back again on the other side.
8. In combination, a hollow piston having a chamber adjacent the inner wall thereof, said chamber being divided into intercommunicating compartments by a diagonally disposed baffle, a cylinder in said piston communicating at opposite ends with different compartments and an inertia operated plunger in said cylinder.
9. In combination, a hollow piston adapted to reciprocate within a cylinder, said piston having a chamber for a cooling fluid adjacent the inner wall thereof, a diagonally disposed baffle within said chamber for directing the fluid down one side of the piston and means for directing said fluid up the other side when the piston reciprocates.
10. In an expansion engine, a cylinder, a piston adapted to reciprocate therein, said piston having a chamber therein containing a liquid and extending substantially the entire length of said piston, a crank shaft, a piston rod connected to said shaft and to said piston at a point midway between the ends thereof.
11. In combination, a hollow piston adapted to reciprocate within a cylinder, said piston having a chamber adjacent its inner wall adapted to contain a cooling fluid, means responsive to reciprocation of the piston for causing circulation of the fluid, and an expansion chamber associated with said first mentioned chamber.

In testimony whereof I have affixed my signature.

ELMER A. SPERRY.
